A. H. PEYCKE,
METHOD OF MAKING REVERSIBLE FULCRUMS,
APPLICATION FILED MAR. 20, 1920.

Patented Feb. 28, 1922.

UNITED STATES PATENT OFFICE.

ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

METHOD OF MAKING REVERSIBLE FULCRUMS.

1,407,886.

Specification of Letters Patent. Patented Feb. 28, 1922.

Application filed March 20, 1920. Serial No. 367,368.

To all whom it may concern:

Be it known that I, ARMAND H. PEYCKE, a citizen of the United States, residing at Chicago, in the county of Cook and State 5 of Illinois, have invented certain new and useful Improvements in Methods of Making Reversible Fulcrums, of which the following is a specification.

This invention relates to a method of making reversible fulcrums.

The object of this invention is to simplify and improve the method of making brake beam fulcrums.

This and other objects are accomplished 15 by means of the method disclosed on the accompanying sheet of drawings, in which—

Figure 1 is a perspective view of a blank used to form the strut of the brake beam fulcrum;

20 Figure 2 is a perspective view of the same blank after having been stretched or elongated;

Figure 3 is a perspective view of the same blank after same has been stretched an increased amount and provided with enlarged 25 portions for strengthening purposes;

Figure 4 is a perspective view of the same blank after the ends thereof have been offset a given amount and the intermediate portion 30 of the blank provided with a tension rod seat;

Figure 5 is a perspective view of another blank or lever supporting member;

Figure 6 is a key for retaining the reversible lever supporting member in one of a plurality of positions; and

Figure 7 is a plan view of the completed brake beam fulcrum.

The various novel features of the invention 40 will be apparent from the following description and drawings, and will be particularly pointed out in the appended claims.

Referring to the figures of the drawings, it will be noted that I first provide a blank, 45 preferably in the form of a steel bar 10. This bar is then heated and subjected to pressure, whereby all parts, with the exception of the middle 11, of the blank are elongated. The blank is then subjected to further treatment or pressure, during which the portions 12 and 13 of the blank are 50 enlarged, the portions 13 being located adjacent the middle portion 11 of the blank. The bar is then placed under a forge ham-

mer for further treatment, at which time the 55 tension rod seat 14 is formed, also trunnion receiving portions 21 and 22, and the ends 15 offset.

A second blank 16, in the form of a lever supporting member, is provided, having a 60 lever receiving opening 17 and trunnion portions 18 and 19, the latter being provided with keyways 20 for the reception of a key 23, which retains the reversible lever supporting member 16 in a plurality of different 65 positions. The blank 16 is then applied to the formed blank 10, so that the trunnion portion 18 is placed within the trunnion receiving portion 21 at the tension rod end of the strut. The blank 10, or 70 rather the legs thereof, are then bent around the lever receiving member as shown in Figure 7 of the drawings, the extremities 15 of the legs being bent laterally, to be riveted in a well known manner to the compression 75 member of the truss type of brake beam. The key 23 is shown inserted to hold the lever supporting member 16 in one of its positions.

It will be understood that the lever receiving member 16 is rotatably mounted between the legs of the strut 24, making the fulcrum reversible.

It is my intention to cover all modifications of the invention falling within the 85 spirit and scope of the following claims.

I claim:

1. The method of making a fulcrum, consisting first in providing a lever supporting member, then providing a blank, then 90 forming a tension rod seat intermediate the ends thereof, and then bending the blank intermediate its ends to form a strut embracing and revolubly receiving the lever supporting member. 95

2. The method of making a fulcrum, consisting first in providing a lever supporting member, then providing a blank, then forming a tension rod seat and trunnion receiving portions therein, and then bending said 100 blank around said lever supporting member to form a strut.

3. The method of making a fulcrum, consisting first in providing a lever supporting member having trunnion portions, then providing a blank, then providing said blank with a tension rod seat and a trunnion receiving portion in the middle of said blank, 105

and providing said blank with cooperating trunnion receiving portions intermediate the ends of said blank, and then bending said blank intermediate its ends to form a strut 5 embracing the lever supporting member, with the trunnions of the latter within the trunnion receiving portions of said blank.

4. The method of making a fulcrum, consisting first in providing a blank, forging 10 a tension rod seat therein, and then bend-

ing the blank around a lever supporting member.

5. The method of making a fulcrum, consisting first in providing a blank, forming a tension rod seat therein, and then bending the blank around a lever supporting member. 15

Signed at Chicago, Illinois, this 27th day of February, 1920.

ARMAND H. PEYCKE.
